UNITED STATES PATENT OFFICE.

JOHN BROOKES CHADWICK AND PETER HOLLINSHEAD, OF RUNCORN, ENGLAND,
ASSIGNORS TO THE SALT UNION, LIMITED, OF LIVERPOOL, ENGLAND.

METHOD OF WORKING GAS-PRODUCERS OF THE MOND TYPE.

1,210,598.

Specification of Letters Patent.

Patented Jan. 2, 1917.

Application filed July 12, 1912. Serial No. 709,118.

To all whom it may concern:

Be it known that we, JOHN BROOKES CHADWICK and PETER HOLLINSHEAD, both subjects of the King of Great Britain, residing, respectively, at 1 Stanley Villas and The Beeches, Weston Road, both in Runcorn, in the county of Chester, England, have invented certain new and useful Methods of Working Gas Producers of the Mond Type, of which the following is a specification.

This invention relates to the working of gas producers of the Mond or by-product type and consists in adding lime to the fuel, the object being to lessen the deficiencies and inconveniences which result when using bituminous fuels so that the working may be accomplished with greater economy than heretofore. In the working of such producers according to the method ordinarily and universally adopted, in which the fuel is fed to the producers and subjected therein to the action of air and steam it is found that the output of ammonia falls considerably below the desired quantity and the gas is of a low calorific value. Moreover most bituminous fuels have a considerable tendency to fuse together or cake, thereby causing great inconvenience and entailing a great amount of labor.

According to the present invention the bituminous fuel is mixed with lime, so that the efficient working of the producers is obtained with a considerable increase in the output of ammonia and a raising of the calorific value of the gas as well as the prevention of the caking of the fuel. In order that the said invention may be clearly understood and readily carried into effect, we will proceed to describe the same with reference to the accompanying diagrammatic drawing showing one method of mixing the lime with the fuel and conducting the same to the producers.

45 *a* is a truck containing coal or fuel and *a'* a receptacle containing lime, the truck and receptacle being arranged in such manner as to allow of the coal and lime being dumped into a receptacle or chamber *a'*.
50 A bucket chain elevator *b* or the like is adapted to raise the mixture of coal and lime from the chamber *a'* to another conveyer *b'* of the Archimedean screw type and this latter conveyer is adapted to convey 55 the mixture to the hoppers *c* which are ar-

ranged in a series or row above the respective producers *d*.

The fuel is fed into the upper part of the producer as required and allowed to enter the same in a manner well known to those accustomed to work power gas producers, the ashes being removed from a water lute *e* at the bottom of the producer.

According to the ordinary practice it is found that from about 60% to 70% of the nitrogen contained in the fuel combines with the nascent hydrogen, which is formed by the steam in the blast passing over the incandescent bed of fuel, to form ammonia the greater portion of the uncombined nitrogen passing away in the gas as free nitrogen. The gas contains only about 27% hydrogen and heretofore only fuel which has low caking tendency has been deemed suitable for use in producers.

The present invention is designed to render possible the employment of fuels of a greater caking tendency; to effect the combination of a larger percentage of the nitrogen contained in the fuel with the nascent hydrogen, and to produce a gas containing a higher percentage of hydrogen. To this end therefore lime is introduced into the gas producer, so as to bring about a considerable increase in the yield of ammonia and at the same time counteract or lessen the tendency of the fuel to cake.

It has been found that the best results are obtained by introducing the lime in the form of a hydrated powder, intimately mixed with the fuel and this mixing is accomplished while the fuel is in bulk in the aforesaid receptacle *a'* previous to being elevated to the hoppers *c* of the producer. The aforesaid method of introducing and mixing the lime at the foot of the elevator is very convenient as it is found that, owing to the action on the fuel by the elevator *b'* and the passage thereof through the conveyer, the fuel becomes thoroughly covered with a coating of the lime before it enters or is admitted to the producer. A 1% addition of the hydrated lime powder has been found to bring about a considerable increase in the yield of sulfate of ammonia and also of the hydrogen in the gas. The fine coating or dusting of the hydrated lime moreover retards the tendency for fusing together of the fuel, and thus prevents the particles caking together and forming a

solid mass in the producer. Therefore, by the employment of the improved method of working, fuels may be used which have the heretofore objectionable tendency to cake to a high degree.

What we claim and desire to secure by Letters Patent of the United States is:—

The method of increasing the ammonia and hydrogen output in the manufacture of producer gas including intimately mixing lime with the coal, burning the coal in a

producer, and passing steam through the burning mixture in such quantity as to reduce the temperature to a point below that of the breaking up of the ammonia.

In testimony whereof we affix our signatures in presence of two witnesses.

JOHN BROOKES CHADWICK.
PETER HOLLINSHEAD.
